UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR-CASE BODY.

SPECIFICATION forming part of Design No. 18,877, dated January 22, 1889.

Application filed December 28, 1888. Serial No. 294,875. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor-Case Body, of which the following is a specification, reference being had to the accompanying drawing, forming part thereof.

Said drawing represents in front elevation a photograph-exhibitor-case body embodying our design, the lid or cover being absent or understood to be thrown back out of sight.

The leading feature of our design consists in the substantially half-elliptic or half-oval shaped photograph-exhibitor-case body having upon one of its sides a curved rib or bead corresponding with the curved edge portion of said side.

In the said drawing, A indicates the substantially half-oval-shaped photograph-exhibitor-case body, which said form provides it with substantially half-oval-shaped front and rear sides, whereof one side, a, which may be considered as the front side, is herein shown. Said side a is ornamented by a rib or bead, B,

substantially concentric with the curved edge portion a' of said side, whereby the said rib 30 relieves the otherwise flat appearance of the side of said body and harmonizes with its curvature. The opposite side of the body, which corresponds to side a, can of course be likewise ornamented, or it can be left plain or 35 otherwise.

While the general effect could to some extent be produced by arranging a representation of the rib or bead B flush with the plane of side a, or by depressing the said side along 40 a line so as to resemble said raised rib, the raised form is more desirable, since it is more striking and distinctive in appearance.

What we claim is—

The design for a photograph-exhibitor-case 45 body, consisting of the substantially half-oval-shaped case-body A, having upon its side a rib or bead, B, arranged substantially concentric with the curved edge of said side, substantially as shown and described.

GEORGE M. PORTEOUS.
FREDERICK S. MILLER.
